UNITED STATES PATENT OFFICE.

JOHN BIGELOW, OF PHILADELPHIA, PENNSYLVANIA.

HAT-BRIM-CURLING MACHINE.

SPECIFICATION forming part of Letters Patent No. 395,118, dated December 25, 1888.

Application filed July 2, 1887. Serial No. 243,250. (No model.)

To all whom it may concern:

Be it known that I, JOHN BIGELOW, a citizen of the United States, and a resident of Philadelphia, Pennsylvania, have invented 5 certain Improvements in Hat-Brim-Curling Machines, of which the following is a specification.

My invention consists of certain improvements in the construction of hat-brim-curling 10 machines of the class shown in Kelsey's patents, Nos. 260,298 and 295,650, which improvements are fully described and specifically 15 claimed hereinafter, reference being had to the accompanying drawings, in which—

Figures 1, 2, and 3 are transverse sections 20 of sufficient of a hat-brim-curling machine of the class referred to to illustrate my invention, the parts being in different positions in the three views. Fig. 4 is a longitudinal section on the line 1 2, Fig. 1. Fig. 5 is a plan view, the hat and upper curls being removed. Figs. 6 and 7 are transverse and longitudinal 25 sections, respectively, of the lower die; and Figs. 8 to 12, inclusive, are views showing other forms of die embodying my invention.

Referring to Figs. 1, 2, and 3, A represents 30 part of the table of the machine having guides, between which slide the heads B B, which carry the side pressing-flanges, c, and end pressing-flanges, c'. The heads B B are connected to a double-armed lever, C, by rods C' in the same manner as in the patents above referred to. Projecting from the center of the table is a flange, d, over which fits snugly 35 the dish D, which is of the peculiar form shown in Figs. 1 and 4. The dish may be supported adjustably as regards height by a set-screw, d', acting either directly or through the medium of a spring, d, so as to render the 40 effect of the closing of the pressing-flanges over the top of the curls similar to that of ironing on the felt of the hat-brim.

As shown in Figs. 1 and 4, the dish D contains a bag, E, of the peculiar form shown in 45 Fig. 6, this bag conforming to the general shape of the hat-brim—that is to say, it is oval in outline, tapered or outwardly-beveled at each end to accord with the dip of the front and rear portions of the brim, and having a 50 concave or inwardly-beveled upper surface at each side where it acts upon the roll of the

brim. The bag has an inlet-pipe, e, which can be placed in communication with a pump or reservoir containing fluid under pressure, the pipe being provided with a suitable stopcock, e', for cutting off the supply of fluid when the bag is filled. 55

I is the hat-block, secured to the dish D by a suitable set-screw or clamp, i, that will hold it in place against upward pressure and yet 60 permit it to be readily detached when a hat of a different size has to be acted upon.

J J are the curls or formers, over which the hat-brim is molded and curled, as shown in Fig. 3. These curls may be loose or may be 65 attached to suitable arms, as shown in the Kelsey patents above referred to.

In the drawings, I have shown detached 70 curls and presser-arms K K, having adjustable plates k, which are provided with adjustable pressing-pins k' for bearing upon the curls. I make no special claim upon this feature of construction in the present application, however, as it forms part of a prior application, Serial No. 228,729, filed by me on 75 the 24th day of February, 1887.

The front and back pressing-flanges, c', are secured to the side pressing-flanges, c, by bolts c², which pass through inclined slots in the sliding flanges c', whereby the closing of the 80 side pressing-flanges, c, will also, owing to the inclined slots and the bolts c², effect the closing of the front and back slides, as in the former Kelsey machine.

When a certain sized hat is to be curled and 85 set, I first clamp together the proper curls, J J, and then place them in the correct position upon the bag E. The pressing-flanges are then moved to the position shown in Fig. 3, and water, air, or other fluid is admitted to 90 the bag E until the latter is filled, as shown in Fig. 3, and conforms to the shape of the under side of the curls J, the supply of fluid being then cut off, the flanges retracted, and the curls released. A hat having its brim 95 portion softened and rendered flexible by heat or otherwise is then placed over the block I and the curls J placed in position on the brim, as shown in Fig. 2, and subjected to pressure. As all escape of fluid from the bag E is cut 100 off, said bag must necessarily conform to the shape of the under surfaces of the curls and

present a solid backing for the brim of the hat. The pressing-flanges cc' are then forced partly over the curls by the operation of the lever C, so as to draw the brim closely against the curls, and the depressors K are then raised

5 and the inward movement of the curling-flanges completed, as shown in Fig. 3, so as to flatten and press the curled edges of the brim.

10 It will be noticed that the under side of the brim, which constitutes the roll of the hat, is formed by the pressure of the fluid-bag, this pressure being exerted first at the inner portion of the roll next the crown and then 15 gradually extending to the outer portion of the roll, so as to press the edges of the brim up into the path of the side pressing-flanges, c , by the inward movement of which the curling of the brim is effected, so that a smoothly-finished roll and a very sharp and even 20 curl of the brim are insured.

Not only is the action of the fluid-bag or 25 flexible under die more effective than that of the usual solid die, but said flexible under die is capable of use for every sized hat which 30 has to be made, thus dispensing with the use of a separate under die or dish for each size of hat. The upper shell of the die is preferably thickened at and near the inner portion 35 of Figs. 6 and 7, so that it will possess a greater degree of flexibility at the outer portion of the roll of the brim than at the inner portion of the same, the necessary movement of the die being greatest at said outer portion.

It is not necessary in carrying out my invention that the die should be made in the form of a bag detachable from the dish of the machine, as said dish itself may form a 40 fluid-receptacle and be provided with a flexible covering, as shown, for instance, in Figs. 8 and 9.

The die may be solid at the ends, if desired, as shown in Fig. 10, these portions of hat-brims being generally of uniform dip, which 45 is unaffected by the different shapes of the curled portions of the brim; hence in many cases a lower die having its side portions only flexible will answer the purpose.

50 My invention may also be carried out without the use of a fluid-filled die, as I may use a solid die, of rubber or other material, possessing such elasticity that it will conform to the shape of the upper curls when the hat-brim 55 is pressed down by the same upon the lower die. (See Figs. 11 and 12.)

It will be seen that although the trouble and expense of providing a number of lower dies, one for each shape of hat-brim, is overcome 60 by my invention the die is as convenient as a solid die and does not necessitate any change in the working parts of the machine.

It should be understood that the terms "lower" and "upper," as used in this specification, do not necessarily apply to the location of the dies in the machine, but simply 65 designate the portions of the brim upon which

the dies act, as it is evident that my invention will not be affected by a change in the location of the parts in the machine so long 70 as they preserve their proper relative position.

I am aware that it has often been proposed to use and that numerous patents have been granted which illustrate and describe the use 75 of flexible pressers in hat-pressing machines, the presser being sometimes solid and elastic, sometimes in the form of boxes which are provided with rubber or like flexible diaphragms for acting on the hat, and which receive water or other fluid from a pump or reservoir under pressure to distend the diaphragms, and sometimes in the form of boxes having rubber diaphragms and containing a confined volume of air or water or a granular 80 mass which will conform to the desired shape, the elastic or flexible bag-pressers having been proposed both for pressing hat crowns and brims. The usual flexible bag-presser, however, when employed for forming the brim 85 of the hat, has a diaphragm much larger than said brim, and this diaphragm is caused by the pressure to overlap the edges of the upper dies, and thus form not only the roll but the curl of the brim as well.

90 I find that it is much preferable to use a flexible die of limited size, the upper surface of which, before the pressing operation, conforms to the general shape of the brim with its dip and roll, and during the pressing operation acts only upon the under side of the brim, so as to press the same against the adjacent faces of the upper curls, reliance being 95 placed upon the pressing-flanges to cause the inward bending or curling of the edge of the 100 brim, as a much more effective means for the purpose than would be afforded by a flexible presser.

Without claiming, broadly, therefore, a flexible presser for the hat-brim, or a presser containing a confined volume of fluid, I claim as 110 my invention and desire to secure by Letters Patent—

1. The within-described die for a hat-brim-curling machine, said die having an upper 115 surface conforming to the general shape of the brim with its dip and roll, and constructed to act upon the under side of the brim only, that portion of the die which acts upon the roll of the brim being flexible, all substantially as specified.

2. The within-described die for a hat-brim-curling machine, said die having an upper 120 surface flexible throughout and conforming to the general shape of the brim with its dip and roll, said upper surface being such as to act upon the under side of the brim only in pressing, all substantially as specified.

3. The within-described die for a hat-brim-curling machine, said die having an upper 125 surface conforming to the general shape of the brim with its dip and roll, the roll portions of the die being hollow and filled with fluid, all substantially as specified.

4. The within-described die for a hat-brim-curling machine, said die consisting of a casing, hollow and fluid-filled throughout, and having a flexible upper surface which conforms to the general shape of the brim of the hat, all substantially as specified.
5. The within-described die for a hat-brim-curling machine, said die constituting a unitary and self-contained structure independent of and detachable from the machine, and having a flexible upper surface conforming to the general shape of the brim of the hat, all substantially as specified.
- 10 6. The within-described die for a hat-brim-curling machine, said die consisting of a flexible fluid-filled casing, constituting a unitary and self-contained structure independent of and detachable from the machine, all substantially as specified.
- 15 7. The within-described die for a hat-brim-curling machine, said die conforming to the general shape of the hat-brim, having a central opening for receiving a projecting portion of the dish of the machine, and possessing such flexibility that it will adapt itself to the shape of the curls when subjected to pressure, all substantially as specified.
- 20 8. The within-described die for a hat-brim-curling machine, said die consisting of a flexible fluid-filled casing, that portion of the latter which acts upon the hat varying in thick-
- ness, so as to vary in flexibility in different parts, all substantially as specified.
9. The combination, in a hat-brim-curling machine, of a dish having a recessed face, 35 with a lower die adapted to said recessed face of the dish, and possessing such flexibility that it will adapt itself to the shape of the curls when subjected to the pressure of the same, all substantially as specified.
- 40 10. The combination, in a hat-brim-curling machine, of the upper curls, the side pressing-flanges, and a lower flexible die for acting upon the brim of the hat, all substantially as specified.
- 45 11. The combination, in a hat-brim-curling machine, of the upper curls, the side and end pressing-flanges, and the lower flexible die for acting upon the brim of the hat, all substantially as specified.
- 50 12. The within-described bottom board or lower die for a hat-brim-curling machine, said die having a flexible portion for acting upon the under side of the brim, and a central rigid portion, all substantially as specified.
- In testimony whereof I have signed my name to this specification in the presence of two subscribing witnesses.

JOHN BIGELOW.
